UNITED STATES PATENT OFFICE.

HAMILTON LINDSAY, OF WILLOUGHBY, OHIO.

CONVEYING DEVICE FOR LOCOMOTIVE-STOKERS.

1,386,416.

Specification of Letters Patent. Patented Aug. 2, 1921.

Application filed April 12, 1919. Serial No. 289,742.

To all whom it may concern:

Be it known that I, HAMILTON LINDSAY, a citizen of the United States, residing at Willoughby, in the county of Lake and State of Ohio, have invented a certain new and useful Improvement in Conveying Devices for Locomotive-Stokers, of which the following is a full, clear, and exact description, reference being had to the accompanying drawings.

This invention relates to a conveying device adapted primarily for use on locomotives for automatically carrying coal from the tender to a point adjacent to the fire box. My conveyer is well adapted for feeding coal substantially continuously to an automatic throwing device which projects comparatively small amounts of coal into the fire box. Such a device is shown, described and claimed in my prior application No. 196,128, filed October 12, 1917, of which the present application is in the nature of a division.

The object of the present invention is to provide simple and efficient means for automatically receiving the coal from the tender and propelling it to a point adjacent to the fire box by a mechanism which is designed to prevent the coal becoming compacted in its travel and which is not interfered with by varying sizes or conditions of the coal. The invention is hereinafter more fully described in connection with an approved embodiment shown in the drawings, and the essential characteristics are summarized in the claims.

In the drawings, Figure 1 is a sectional side elevation of my conveyer embodied on a locomotive and tender, portions of which are shown; Fig. 2 is a plan of the conveyer shown in Fig 1 with parts in section and some parts broken away; Fig 3 is a side elevation taken from the opposite side to Fig. 1; Fig 4 is a perspective view of the conveyer box on the tender; Fig. 5 is a plan of the plunger in the locomotive conveyer; Fig. 6 is a side elevation of such plunger; Fig. 7 is a plan of the conveyer box on the locomotive; Fig. 8 is a side elevation of such box; Fig. 9 is a horizontal section on the line 9—9 of Fig. 8; Fig. 10 is a transverse section on the line 10—10 of Fig. 7; Fig. 11 is a cross

section of the locomotive plunger as indicated by the line 11—11 on Fig 5; Fig. 12 is a cross section of the tender plunger as indicated by the line 12—12 on Fig. 2.

In Figs. 1 and 3, A indicates the rear end of a locomotive fire box, B the floor of the cab, C the floor of the tender, D the bridge plate extending from floor to floor. The conveyer mechanism constituting the subject matter of this invention is carried beneath the respective floors and bridge plate and is adapted to convey the coal from the tender to a position at the rear of fire openings G through the rear wall of the fire box.

Fitted around the openings G, are the forward ends of long box-like casings extending rearwardly and downwardly beneath the deck B, of the locomotive. These casings are indicated at 1 and 2 and preferably are made in the nature of sheet metal boxes, the side walls of which are enlarged adjacent the fire box and secured thereto by angle brackets 3, each having one flange secured to the box side and the other secured to the boiler plate A. The casing preferably has its side walls and bottom composed of plates and angles riveted or welded together as shown in Figs. 7—10, while being closed for a greater part of its length by a removable top plate 4, carrying a hopper 5. Within the housings 1 and 2, are plungers, for conveying the coal forwardly toward the fire box, and means for intermittently throwing a small portion of the coal through the opening G, as will be hereinafter described.

The coal is brought from the tender along box-like conveyers or chutes 6 and 7 secured to the under side of the tender deck C, and extending forwardly therefrom over the hoppers 5. These boxes are also preferably constructed of rolled metal and angles as shown in Fig. 4 and are open at both ends.

Within each of the housings or chutes 1, 2, 6 and 7 are peculiarly shaped plungers arranged to advance the coal along the housing and designed to avoid wedging or clogging thereof. These housings are smooth on their interiors and the plungers which are preferably cast metal members fit slidably in each housing, the removable covers on the housings 1 and 2 and the open ends of the housings 6 and 7 permitting easy assembling.

The plungers within the chutes 1 and 2 comprise approximately U-shaped castings, each having a transverse portion 10 at its rear end and forwardly extending portions 11 5 stepped on their inner sides as indicated at 12, 13, 14 and 15 in Figs. 2 and 5. The portions 12 to 15 inclusive join vertical inner walls and all these parts are integral with substantially horizontal webs 18 and 19. 10 Suitable strengthening vertical webs 17 are located between the webs 18 and 19. The horizontal webs 18 and 19 and the vertical webs 17 all terminate at the outer sides of the plungers which fit slidably in the housings 15 mentioned.

The transverse wall 10 and the shoulders 12 to 15 form the surfaces which urge the coal forwardly and upwardly along the housings when the plunger is reciprocated. The 20 coal being admitted adjacent to the wall 10 between the walls 11, as it moves upwardly is allowed to spread laterally, thus entirely avoiding any packing or wedging and consequently rendering the movement of the 25 coal comparatively easy. The top and bottom members 18 and 19 closely meet the top and bottom walls of the boxes 1 and 2 on the locomotive and the bottom of the box and the under side of the tender floor on the 30 tender, while in each case the outer edges of these plunger portions form a close connection with the side walls of the conveyer boxes, thus preventing even the fine particles 35 of coal from wedging between the plungers and walls of the boxes.

The hoppers 5, receiving the coal from the forward ends of the chutes 6 and 7, bring the coal to the reduced receiving space of the plunger between the walls 11 of the 40 locomotive plungers. To prevent any of the coal in the hopper from catching between the upper portion of the wall 10 and the forward edge of the hopper, I provide a hinged plate 20, pivoted at 21 to the cover 45 4 and having its rear end rounded inwardly and downwardly so that a piece of coal coming between the wall 10 of the plunger and the rounded portion of this plate at 22, may raise the plate sufficiently to prevent its 50 wedging or breaking any of the parts. To retain the coal against backward movement with the plunger in case gravity will not sufficiently hold it I may provide on the under side of the plate 20 hinged fingers 25 capable of swinging forwardly but stopping in their rearward movement in substantially vertical position. The coal may pass these 55 fingers freely on the forward movement but lodges against them on the return movement 60 of the plunger.

The downward movement of the cover is limited by the downward movement of the strip 23, while a weight 24 urges this plate downwardly so that recession of the plunger 65 bringing a wider portion between its walls

thereof below this plate 20 may allow the plate to press any lumps downwardly into the mass of coal in the chute.

The plungers in the chutes 6 and 7 are substantially the same construction as those 70 just described, each having a rear transverse portion 30, and forwardly extending portions 33. These forwardly extending portions are stepped outwardly by shoulders designated 34 and longitudinal surfaces 75 35. The extreme ends of these plungers are beveled at their forward ends as shown at 37 to gather the coal inwardly to a certain extent and insure its readily passing 80 into the hoppers 5.

I find that by employing the stepped reciprocating plungers described, in both the locomotive conveyers and the tender conveyers, I can positively feed small amounts 85 of coal and at the same time keep the mass of the coal in the housings constantly loosened so that it will not clog.

In the deck C of the tender are openings 90 preferably substantially twice the length of the movement of the plunger and the plungers in the boxes 6 and 7 have near their rear ends inwardly projecting horizontal flange ears 38 at their first steps as shown in Figs. 2 and 12, so that the plunger opening may align with the opening 39 in the 95 tender floor irrespective of the position of the plunger. The upper webs 33 of these plungers extend rearwardly far enough to prevent the coal dropping behind the 100 plungers.

The mechanism for actuating the plungers is correlated with mechanism for operating the throwing device at the forward end of the conveyer. I will first describe the plunger actuation and then give a brief description 105 of the particular throwing mechanism shown, though it is to be understood that the throwing mechanism shown is described and claimed in my prior application referred to, and the conveyer of the present 110 application may be used in connection with any suitable throwing mechanism.

Preferably secured to one of the cross beams K of the locomotive frame is a shaft 115 55 extending transversely beneath the chute 1 and journaled to the beam K by suitable brackets 56. As a means for actuating the two plungers in the chutes 6 and 7 simultaneously, I may connect those plungers with the shaft 55 in the following manner: 120 Secured to the plunger by pins 58 fitting in holes 59 in the plungers is a cross bar 60. Secured to the cross bar 60 are ears 61 to which is pivoted a link 62, the forward end of which is pivoted to a lever 65 pivoted at 125 66 to a bracket 67 secured to the under side of the tender conveyer box. The lower portion of this lever 65 connects with a link 70 having an extension 71 pivoted to a rock arm 72. An intermediate joint 75 is prefer- 130

ably provided between the links 70 and 71. These various pivots allow universal play to accommodate relative movement of the tender and locomotive.

5 The rock shaft 55 carries another upwardly extending arm 76 rigid thereon and pivoted to a shift link 77, in turn pivoted to bracket ears 78 rigid with a cross beam 80, connected with the plungers in the same 10 manner as the cross beam 60. This cross beam operates in longitudinal openings in the inner side walls of the chutes 1 and 2.

It will be seen that the actuation of the rock shaft 55 will cause simultaneous movement of the two sets of plungers, the plungers on the tender moving in one direction while the plungers on the locomotive are moving in the opposite direction.

I prefer also to make the lower portion 20 of the lever 65 longer than the upper portion, or I may provide an adjustment in the arms 72 and 76, to cause the forward plungers to move a greater distance than the plungers on the tender, with the result that 25 the coal cannot be fed by the rear plungers fast enough to congest the passages of the forward plungers.

As a convenient means for actuating the shaft 55 and accomplishing the movement 30 of the plungers, as well as the movements of the throwing blades and other parts, I have illustrated at 85 a steam engine cylinder having a driving connection with a worm 87 meshing with the worm wheel 88 driving a connecting rod 89 pivoted at its 35 lower end to a rock arm 90 rigid on the shaft 55.

Rigid on the shaft 55, is a face cam 92 having a groove 93, embracing a pin or stud 40 94 projecting from an arm 95 pivoted as shown at 96 to a bracket on the bottom of the plunger box 2. Upon the reciprocation of the shaft 55, the cam 92 is oscillated swinging the lever 95 upwardly and 45 downwardly, which acts through a link 97 pivotally connected to the lever 95 and to an arm 98 on a shaft 100, extending transversely across the face of the inclined end A of the boiler and beneath the forward ends 50 of the chutes 1 and 2. The arm 98 is keyed to the shaft 100, and arms 102, also rigid with the shaft, are connected by links 103, with the projections 104 integral with the bracket arms 48 beneath the throwing 55 blades, whereby the oscillation of the rock shaft 100 swings the brackets 48 carrying the stop flanges 49 upwardly.

The throwing devices which receive the coal discharged at the forward ends of the 60 conveyers include throwing blades or shovels 45 (one for each conveyer) mounted on a transverse shaft 46 extending through the forward end of the boxes 1 and 2 and closely adjacent to the fire wall A. The rock shaft 65 46 is intermittently rotated through a suffi-

cient number of degrees to move the shovel or throwing blade upwardly from the position shown in Fig. 3. The shovel normally rests upon a swinging bracket arm, loosely journaled to the shaft 46 at each side of the 70 connections of the blade 45 to the shaft, as indicated at 48 and extending rearwardly beneath the shovel or blade and carrying at the rear end thereof an upturned flange 49 adapted to stop the progress of coal, when 75 the shovel is moved upwardly to throw its load into the fire box. When the flange 49 is in its up position, it overlaps the lower edge of an arcuate cover plate 50 hinged by a rod 51 to the side walls of the 80 boxes 1 and 2. The downward movement of the cover is limited by a strip 52 having its ends overhanging the side walls as indicated in Fig. 7. The bracket arms 48 and the throwing blade 45 are moved through 85 their respective arcs at the proper time to accomplish the throwing of coal into the fire box and to allow coal to fill up back of the flange 49, while the blade is absent from the receiving position. 90

The means for giving the throwing blades a sudden upward and forward movement is shown as follows: A short arm 105 on the shaft 46 on which the throwing blades are rigidly keyed, is connected by a link 106 95 with an actuating lever 107 pivoted at 108 to a bracket 109 secured to the transverse I-beam K, of the locomotive. The lever 107 carries a laterally extending cap 110 in which seats one end of a compression spring 100 112 having its lower end seating in a cap shown at 113. On the shaft 55 is a cam 115 coacting with a roller 114 rigid on the arm 107 to depress that arm and compress the spring 112 to the position shown in Fig. 1 105 where it is latched. A hinged strut 117 attached at 118 to a bracket 111 is adapted to bear its lower end against a lug or roller 120 carried on the arm 107, thus holding this arm down with the spring 112 compressed 110 and the throwing blade or shovel 45 in its receiving position. At the same time the arm 95 is actuated by the cam 92 and the connections with the flange stop 49 are so positioned that these stops are lowered, 115 allowing coal to pass across them and onto the throwing blades.

After a predetermined amount of coal has been deposited on the throwing blade by the forward movement of the plunger, the upward movement of the lever 95 actuates the rock shaft 55 to cause the cam 92 to swing the lever 95 upwardly, thus raising the stop flange 49 through the connections described. The actuation of the rock shaft 100 in this 120 movement causes the latch strut 117 to release the lever 107, allowing the spring to thrust its forward end upwardly quickly, which, through the link and arm 106 and 105 respectively, causes the blades 45 to swing 130

upwardly and forwardly sharply, thus throwing the coal forcibly through the openings G.

The dropping of the lever 107 by moving the strut 117 off from the roller 120, may be caused by a jointed arm 122 keyed to the shaft 100, and carrying a roller 126 at its free end. By an upward movement of the jointed arm 122, the roller 126 may engage a cam 129 on the latch 117 to swing the latch rearwardly off from the roller 120, permitting the lever 107 to swing upwardly and actuate the shovels, as described.

On the downward movement of the arm 122 the latch 117 is swung forwardly by a weight 121 rigid with the arm. Accordingly the roller 120 engaging this cam on its downward movement is arrested, while the jointed arm 122 continues allowing the roller to pass the cam. Thus the cam 115 may depress the lever 107 and the latch may engage the roller 120 to set these parts in their lowermost position, and a subsequent downward movement of tripping lever 122 is prevented by its flexing movement from prematurely tripping the mechanism operating the throwing blades.

The lower cup for the spring 112 is shown as pivoted at 130 and rigidly attached to a lever 131, extending upwardly into the cab and having the usual dog 132 operated by a grip handle rod 133 and adapted to engage a rack 134 secured to the cab floor, whereby the lever may be held in various positions, allowing the raising or lowering of the cap 113 to adjust the compression of the spring 112, with a result that distribution of the coal may be regulated by varying the force applied to the throwing blade.

A summary of the operation of my device is as follows: Starting with the plungers in the position shown in Fig. 1, the plungers on the tender are moved to their forward position, causing coal to be thrust forwardly and dropped into the hoppers. The subsequent movement of the connecting rod 89, rocks the shaft 55 moving the arms 72 and 76, swinging them forwardly, which advances the plungers on the locomotive and recedes the plungers on the tender, the latter plungers taking a new charge of coal. Assuming that the arm 107 has been depressed and latched on a previous movement of the shaft 55 and cam 115, the finish of the downwardly movement of the lever causes the plungers to bring the charge of coal onto the throwing blades and the following upward movement of this lever acts through the cam 92, lever 95, hinge 97 and arm 98 to raise the flange stop 49. At the finish of this raising movement the lever 122 causes its roller 126 to release the latch, allowing the spring 112 to raise its lever, the link 106 and lock arm 105, moving the shaft 46 on which both throwing blades 45

are mounted, thus discharging the coal forcibly through the openings G. In case any coal lodges between the flanges 49 and a cover 50, this cover may swing upwardly without injuring the parts.

From the foregoing description it will be seen that I have provided an automatic stoker, comprising a novel plunger arrangement for feeding coal from the tender of the locomotive, not liable to clog or get out of order, and capable of movement by use of but little power; and this may be readily combined with means for throwing and distributing the coal into the fire box in the desired position, actuated by a simple and effective mechanism. My mechanism may operate efficiently with various grades or kinds of coal; thus, I have found that with the embodiment shown in the drawings I can satisfactorily feed coal varying in size from slack to a diameter of four inches.

Having thus described my invention, what I claim is:

1. In a conveying device, the combination, with a casing, of a reciprocating plunger, said plunger having a series of steps on the inner side thereof.

2. In a device of the character described, the combination, with a casing, of a reciprocating plunger therein having two separated portions slidable along the inner wall of the casing and each provided with steps on its inner edge.

3. In a device of the character described, the combination, with a casing, of a reciprocating plunger therein having a head and two projecting portions which lie adjacent to the interior of the casing, each of said portions having a series of steps which extend from the head of the plunger to the extremity of each projecting portion thereof.

4. The combination in a conveyer, of a casing, a reciprocating plunger therein closely fitting the interior walls thereof and having a series of steps on the conveying face, each of said steps having one face which lies in a plane parallel to the direction of travel.

5. In a locomotive stoker, a coal chute and a vertically stepped U-shaped plunger slidably mounted in said chute.

6. In a locomotive stoker, a chute for leading coal to the fire box, and a U-shaped plunger in said chute, the inner side walls of which are arranged in offset steps progressively farther apart toward the forward end, and having a series of intermediate abrupt shoulders.

7. A locomotive stoker comprising a chute on the tender, a chute on the locomotive having a hopper for receiving coal from the first chute, said hopper being positioned intermediate the locomotive and tender, plungers in each of said chutes having a trans-

- verse portion, parallel forwardly extending portions and offset shoulders whereby the receiving or rear portion of the plunger is narrower on the inside than the forward portion thereof. 70
8. In a locomotive stoker, the combination of a horizontal chute on the tender, an inclined chute on the locomotive for leading coal adjacent to the fire box, substantially 10 U-shaped plungers in each of said chutes, provided with stepped legs, and means on the locomotive for actuating each of the plungers, said means being arranged to move the locomotive plunger a greater distance than the plunger on the tender. 80
9. In combination a locomotive, a tender, a coal conveyer on the tender, a coal conveyer on the locomotive, said first named conveyer being adapted to discharge directly into the second, and means on the locomotive for actuating each of the conveyers, said actuating means being arranged to move the plungers simultaneously at different rates of speed and in opposite directions. 85
10. In a locomotive stoker, the combination of a chute on the locomotive for leading the coal to the fire box, a chute on the tender for discharging the coal into the first mentioned chute, stepped plungers in each 90 of said chutes, and means on the locomotive for reciprocating each of said plungers, said means including a connecting rod to the plunger on the tender, said rod having joints adapted to allow universal play. 95
11. In a locomotive stoker, the combination of a conveyer comprising a longitudinal chute, a plunger therein having a transverse rear portion and forwardly separated extending portions, a hopper for directing coal 100 into the chute adjacent to the rear portion of the plunger, and a pivoted member at the top of the chute adapted to rise to accommodate lumps of coal between it and the plunger, and fingers depending from the member 105 and extending into the chute. 110
12. In a locomotive stoker, the combination with a locomotive, of a tender, conveyer chutes on the locomotive and tender respectively, the locomotive chute having a hopper 115 on the end thereof adjacent the tender, a plate on said chute opening upwardly with the free end thereof adjacent the hopper, and means pivoted to the under side of the plate and depending into the chute. 120
13. In a locomotive stoker, the combination of a conveyer comprising a longitudinal housing, a U-shaped plunger therein having a transverse rear portion and a series of forwardly extending stepped portions, a 125 hopper for directing coal into the housing in front of the rear portion of the plunger and between its side members. 130
14. In a locomotive stoker, the combination with a locomotive and a tender, of conveyer chutes on the locomotive and tender re- spectively, plungers in each of the conveyers, means on the locomotive for reciprocating the plungers in the conveyers, said means being arranged to move the plungers simultaneously in opposite directions. 70
15. In a locomotive stoker, the combination of a conveyer comprising a housing, a stepped U-shaped reciprocating plunger therein, a hopper for directing coal into the housing in front of the rear portion of the plunger, a conveyer housing on the tender, a stepped U-shaped plunger therein, and means on the locomotive for operating the plungers of both conveyers. 75
16. In a locomotive stoker, the combination of a conveyer comprising a longitudinal chute, a plunger therein having a transverse rear portion and forwardly extending portions stepped on their inner sides, each of said steps having one face thereof lying in a plane parallel to the direction of travel and another face thereof lying in a plane at right angles to the direction of travel, a hopper for directing coal in front of the rear portion of the plunger, a chute on the tender 90 overhanging said hopper, a plunger therein for feeding coal along such chute, and means on the locomotive for moving the plungers of both chutes. 95
17. In a locomotive stoker, the combination, with a fire box, of a plurality of conveyer casings leading thereto, plungers in said casings for feeding coal therein forwardly, a cross bar connecting said plungers, mechanism on the locomotive for operating the cross bar, hoppers on each of said conveyer casings, conveyers on the tender discharging into said hoppers, respectively, said tender conveyers having plungers, a cross bar connecting them, and mechanism on the locomotive for operating said two cross bars. 100
18. In a conveying device, the combination with a casing, of a reciprocating plunger closely fitting the interior walls thereof, said plunger having a substantially U-shaped stepped conveying face open toward the front. 110
19. A locomotive stoker, comprising a horizontal chute on the tender, an inclined chute on the locomotive having a hopper for receiving coal directly from the first chute, and plungers in each of said chutes. 115
20. A locomotive stoker, comprising independent chutes on the tender and locomotive, the forward end of the chute on the tender extending over the rearward end of the chute on the locomotive at a point intermediate the tender and the locomotive, and plungers in said chutes. 120
21. A locomotive stoker, comprising a chute beneath the cab floor of the locomotive, a chute beneath the deck of the tender, with its forward end overlapping the rearward end of the first mentioned chute, plungers 125

in each of said chutes, and means for moving said plungers, said means comprising a single link joint between the locomotive and single operating connection between the locomotive and the tender. 10

5 22. A locomotive stoker, comprising spaced overlapping chutes on the tender and locomotive, plungers in said chutes and means

for operating said plungers, comprising a single link joint between the locomotive and tender mechanism.

In testimony whereof I hereunto affix my

HAMILTON LINDSAY.
